UNITED STATES PATENT OFFICE.

ABRAM SNYDER BROWN, OF TYRONE, PENNSYLVANIA.

FOLDING LUNCH-BOX.

SPECIFICATION forming part of Letters Patent No. 643,862, dated February 20, 1900.

Application filed August 18, 1899. Serial No. 727,658; (No model.)

To all whom it may concern:

Be it known that I, ABRAM SNYDER BROWN, a citizen of the United States, and a resident of Tyrone, county of Blair, State of Pennsylvania, have invented a new and useful Improvement in Folding Lunch-Boxes, of which the following is a full, clear, and exact description, reference being had to the accompanying drawings, making part of this specification.

10 My invention relates to an improvement in folding lunch-boxes; and it consists in the peculiar construction and arrangement of parts hereinafter more fully described, and particularly pointed out in the claim.

15 In the accompanying drawings, Figure 1 is a perspective view of my improved folding lunch-box, showing the same arranged for use. Fig. 2 is a similar view showing the same folded as when not in use. Fig. 3 is a 20 plan view showing the lunch-box flattened out and extended. Fig. 4 is a sectional view taken on the line $x-x$ of Fig. 2 on an enlarged scale, showing the pasteboard parts, the linings, and covers thereof and the pockets 25 formed between said pasteboard parts and the linings.

The four sides A, B, C, and D of my lunch-box, which are each of rectangular form and are of similar shape, are arranged side by 30 side in series and flexibly joined together on the lines 1 2 3, as shown, and adapted to be folded on said lines.

To the ends of the bottom side B are attached the square end pieces E by flexible 35 joints along the lines 4. Each of these end pieces E is provided on its inner side with a pocket F, which are formed between the said end pieces and the linings thereof, and to the sides of the end pieces are flexibly jointed 40 flaps G, which are triangular in form and adapted to be folded inwardly over the end pieces on the lines 5.

To the outer side of the top side piece D is attached an overlapping flap H, which is connected thereto by a flexible joint along the line 6, and triangular flaps K are flexibly attached to the ends of the top piece along the lines 7. The said flaps H K are thus adapted to be folded over the inner side of the top 45 piece D, as indicated in dotted-lines in Fig. 3.

The side pieces A C are provided at their ends with pockets L M, respectively, which

are formed between said side pieces and their linings, adapted to receive the flaps G of the end pieces when the parts are arranged in 55 position to form a box, as shown in Fig. 1, the side pieces A C being first upturned, the end pieces E being then upturned and having their flaps G inserted in the pockets L M of the side pieces, and as the top piece D is 60 turned down in closing the box its end flaps K are inserted in the pockets F of the end pieces, whereby the said end pieces are effectually prevented from opening while the box is in use. The flap H on the free side of 65 the top piece D folds over and overlaps the outer side of the side piece A, thus effectually closing the joint between the said top and side pieces. A strap O is passed around the box to secure it when filled and to enable it 70 to be easily carried, a loop P being provided on the said strap for the insertion of a finger or for the attachment of a belt or strap around the shoulders of a wearer.

When folding or "knocking down" the 75 box, the flaps G are folded against the inner sides of the end pieces E, the latter are turned outwardly under the bottom piece B, the side piece A is folded on said bottom piece, the side piece C is folded against end pieces E 80 and flaps G, the flaps H K are folded inward against the top piece D, and the latter is then folded against the side piece C, with the flaps H K between them. Hence when the box is thus folded only the outer sides of the side 85 piece A and top piece D are exposed.

I prefer to manufacture my improved folding lunch-box of pasteboard, provided with suitable linings a and covered on the outer sides with cloth, as at b; but the box may be 90 made of leather, wood, metal, or other suitable material, if preferred, as will be readily understood.

When the box is folded, the strap O is passed around it from end to end, as indicated 95 in Fig. 2.

My improved folding lunch-box is exceedingly neat and attractive in appearance, may be very cheaply manufactured and sold for a low price, and is very compact and serviceable.

Having thus described my invention, I claim—

The folding lunch-box comprising the front

side piece A, the bottom piece B, the rear side piece C and the top piece D, arranged in series and flexibly jointed together, said side pieces A, C, having the end pockets L, M, respectively, and said top piece D having the end projecting flaps K, and the side flap H; and the end pieces E flexibly jointed to the ends of the bottom piece B, said end pieces having the pockets E for the reception of the flaps K and being further provided with the

side projecting flaps G adapted to enter the pockets L M of the side pieces, all constructed and arranged substantially as described.

In testimony whereof I have set my hand, this 11th day of August, A. D. 1899, in the presence of two attesting witnesses.

A. SNYDER BROWN.
